UNITED STATES PATENT OFFICE.

JOSEPH W. STOVER, OF NEWTON, MASSACHUSETTS.

APPARATUS FOR SIGNALING BY ELECTRICITY.

SPECIFICATION forming part of Letters Patent No. 255,124, dated March 21, 1882.

Application filed November 18, 1881. (No model.)

To all whom it may concern:

Be it known that I, JOSEPH W. STOVER, of 5
Newton, county of Middlesex, State of Massachusetts, have invented an Improvement in
Methods of and Apparatus for Signaling by
Electricity, of which the following description,
in connection with the accompanying drawings, is a specification.

My invention relates to a method of signaling especially adapted to that class of telegraphy in which the recorded signals consist of different numbers of dots, or are produced by electric impulses of very short duration, and has for its object to enable the signals to 15 be given with greater rapidity than by systems now practiced.

In telegraphing and signaling relays are commonly employed to open and close a local circuit, the currents of which actuate and control the registering mechanism by which a strip of paper is either embossed or receives colored marks by chemical action when permanent signals are desired. As heretofore commonly employed the relay-armature lever 25 closes the local circuit only when it is in one extreme position, either attracted or retracted, and consequently, in giving a series of signals, two movements of the relay-armature toward and from the poles of its magnet are required 30 for each complete signal.

This invention consists partly in causing both the opening and closure of the main circuit to be registered, as hereinafter described, a complete signal being recorded at the movement of the relay-armature from the poles of 35 the magnet, and also at its return movement toward the poles thereof.

The invention also consists in a relay which operates to close the local circuit in the movement of its armature toward and from the poles of its magnet, instead of at the termination of one of the said movements, as has commonly been done.

Figure 1 is a side elevation of a relay adapted 45 for the practice of this invention, it being properly constructed to close the local circuit in its movement in either direction; Fig. 2, a detail showing a different device for controlling the local circuit, the relay-armature being in one 50 of its extreme positions and the local circuit open; Fig. 3, a similar view, but with the relay in an intermediate position and the local circuit closed; Fig. 4, a modification in which the local circuit is closed at the end of the

movement of the armature; Fig. 5, a break-wheel adapted to be used in practicing this invention, and Figs. 6 and 7 strips as registered by the relay shown in Figs. 1 and 4 respectively.

As shown in Fig. 1, the armature-lever *a* of 60 the relay-magnet *b* forms one and the framework *c* the other electrode of the local circuit controlling the register or recording mechanism, which is well known and needs no illustration, such register consisting essentially of 65 a train of wheel-work to move a strip of paper, an electro-magnet in the local circuit to set the said train in movement as soon as a signal begins, it being adapted to stop itself after a definite interval without signals, and a stylus 70 operated by an electro-magnet in the local circuit to emboss the said traveling-paper, or electrodes to cause discoloration of the said paper, chemically prepared for that purpose, when the current is flowing.

The front and back stops, *d e*, for the armature-lever *a* are both provided with insulating material, as shown, so that the said lever does not make electrical connection with either; but the framework *c* has connected therewith 80 a contact-point, shown as a fine spring, *f*, properly located to be touched by the end of the armature-lever as it passes from one to the other of the stops *d e*, but to be disconnected 85 from the said lever when resting against either of the said stops, as shown. The local circuit is thus closed momentarily at each backward and forward movement of the armature-lever *a*, and a series of dots may thus be registered or recorded, as will be readily understood 90 by those familiar with the art, and various different signals may be produced by varying the intervals between the said dots. This method is especially adapted to the sending of number-signals—such as used for fire-alarm and 95 municipal purposes—where a series of dots at uniform intervals represent a figure, a longer interval is employed to separate the different figures of a complete number, and a still larger interval is used to separate the repetitions of 100 the same number. Such a signal, composed entirely of dots, is shown in Figure 6, as it appears when registered upon the paper strip, two repetitions of the signal 314 being given, as indicated by the figures above the different 105 series of dots. These signals are usually transmitted mechanically by a break-wheel, and one adapted for this system is shown in Fig. 5,

where the metallic disk or wheel forms one electrode of the circuit of the relay-magnet *b*, Fig. 1, and a contact-spring, *g*, resting on the periphery of the said wheel forms the other 5 electrode. The said wheel is notched or provided with insulating material in its periphery, as shown, so that as it rotates electrical contact is made and broken between it and the spring *g*, and the relay-magnet and its armature are thus affected in the well-known manner; but as each movement of the said armature is recorded, it will be seen that but one-half the usual number of notches or insulated 10 spaces will be required, the signals being given, as indicated by the numbers marked on the wheel. A broader metallic space or insulated space, as the case may be, is employed to give the longer interval between the dots.

In the modification shown in Figs. 2 and 3 20 the armature-lever *a* does not form a portion of the local circuit, which includes two contact-springs, *f*¹ *f*², mounted on insulating material, and having a metal anvil-piece, *a*², between their free ends, so that when they both touch 25 the said anvil-piece the local circuit will be closed; but if either of them be separated from the said anvil-piece the local circuit will be open. The end of the armature-lever *a* plays between the ends of the said springs, it bearing 30 one of them away from the piece *a*² when it is against either of its stops *d* or *e*, as shown in Fig. 2, but permitting them both to touch the said piece *a*² in its passage from one stop to the other, as shown in Fig. 3.

35 It is not necessary that the relay-armature should close the local circuit during its movement; but it may close it at the end of its movement in the usual manner, except that it closes at both movements. In this case an arrangement such as illustrated in Fig. 4 will preferably be employed. In this one of the armature-stops, as *d*, is in electrical connection with the frame-piece *c*, while the other stop, *e*, is insulated therefrom, and both are adapted to 40 make electrical contact with the armature-lever *a*. The local circuit, as shown in dotted lines, has two branches, one pole of its battery being connected by wire 12 with the armature-lever and the other pole having two branches, 45 13 14, connected with the frame *c* and with the stop *e*, respectively. By this arrangement dashes may be recorded as well as dots, and the register should have two stylus-operating magnets, (indicated in plan view at *l m*,) one in 50 each branch of the said local circuit, and the operation of the break-wheel (shown in Fig. 5) will be registered, as shown in Fig. 7, in which it will be seen that the marks in both lines are counted, a dash indicating the last count of 55 each figure and a long dash indicating the end of the complete number.

When the armature-lever *a* is against the back stop, *e*, as shown in the drawings, the circuit 12 14 will be closed through the magnet 60 *m*, and the stylus, carried by its armature, will be in contact with the registering-strip, the branch 13, containing the magnet *l*, being then

open between *a* and *d*. When the armature-lever *a* is attracted into contact with the stop *d* the circuit 12 13 will be closed through the 70 registering-magnet *l*, the stylus of which will then rest on the paper, while the branch containing the magnet *m* will be opened and its stylus removed. In this case one of the register-magnets will remain in a normally-closed 75 circuit, and the first movement of the armature of the other magnet or the backward movement of the normally-attracted armature may be employed to release the train of wheel-work and set the paper in motion.

80 It is obvious that a single local circuit might be employed, it being closed on both stops *d* and *e*, and in this case a single stylus-magnet would be employed and the record of Fig. 7 would be in one line, the spaces between marks then corresponding to the time occupied by the relay-armature in passing from one stop to the other. This method is useful where it is desirable to send a signal with extreme rapidity and at the same time to enable a permanent record to be 85 kept of such signal. The only limit to the speed of operation is the capability of the armature-lever to respond, and it will be seen that double the speed is attained that can be when 90 only one movement of the said armature is recorded, as is usually the case.

I claim—

1. In an electric signaling apparatus, a relay having a movable armature and retractor and a device for alternately breaking and closing the circuit thereof, combined with a local battery and circuit for operating registering apparatus the terminals of which are controlled by the said relay-armature, as described, whereby the condition of the said local circuit is 100 changed both at the movement of the relay-armature from and at its movement toward the poles of its magnet, and a record is thus made both of the opening and closure of the main or relay circuit, substantially as and for the purpose set forth.

2. In a relay, the combination, with the relay-armature, of the local-circuit terminals controlled thereby and arranged as described, by means of which the local circuit is closed in 115 the movement of the armature in either direction, but retained open at the end of the said movements, substantially as and for the purpose set forth.

3. The combination, with a relay-armature 120 lever forming a portion of the local circuit, and insulating-stops therefor, of a contact-spring, also forming a portion of the local circuit, it being located, as described, relative to the armature-lever, whereby it is touched by the said 125 armature-lever only in its movement from one to the other of the said stops, substantially as described.

In testimony whereof I have signed my name to this specification in the presence of two 130 subscribing witnesses.
